UNITED STATES PATENT OFFICE

JOHN P. ANDERSON, OF KOPPEL, PENNSYLVANIA, ASSIGNOR TO PRESSED STEEL CAR COMPANY, OF PITTSBURGH, PENNSYLVANIA, A CORPORATION OF NEW JERSEY

DUMP CAR

Application filed April 23, 1929. Serial No. 357,568.

An object of my invention is to provide a door locking mechanism which will automatically engage with the doors when in a closed position and lock them in position without assistance from the door closing mechanism.

Another object of my invention is to provide a mechanism that will automatically release the door at the side towards which the body is tilted and permit the door to open by gravity and the weight of the lading being discharged.

Another object of my invention is to provide a door locking mechanism mounted entirely on the car body and controlled by the tilting and righting movements of the body as the body moves in dumping.

For purposes of illustration, the dump car has been shown with the body mounted as in the type of car known as a rotary trunnion dump car in which the body is mounted directly on the underframe and tilts about the underframe during the first part of the dumping movement until trunnions which are mounted on the sides of the body engage with the underframe after which the body tilts about such trunnions as pivots in completing the dumping movement. However, it is to be understood that this type of mechanism will work equally as well where the body is supported on trunnions mounted at each side of the body and in engagement with the underframe and the body tilting about such trunnions at one side of the underframe during the entire dumping movement. The body has also been illustrated as a side dump body, but this mechanism will work equally as well on an end dump body with the exception that the mechanism will be placed longitudinally of the body instead of transversely as illustrated.

Referring now to the drawings, Fig. 1 is a transverse section through a dump car showing the door locking mechanism with the doors in closed position; Fig. 2 is a transverse section through a dump car showing the door locking mechanism with the doors in closed position, and in dot and dash lines showing the position of the door locking mechanism when the body is in fully dumped

position and the discharging door in fully opened position; Fig. 3 is a plan view of a portion of the body with the floor removed showing the method of mounting the locking mechanism; Fig. 4 shows in elevation the portion indicated by the lines 4—4 of Fig. 3; Fig. 5 is a side elevation of the door stake and method of attaching the locking mechanism to the door; Fig. 6 is a section through the locking mechanism along the lines 6—6 of Fig. 3; Fig. 7 is a section through the door locking mechanism along the lines 7—7 of Fig. 3. Since the door locking mechanism illustrated in the drawings requires a separate mechanism for controlling the opening of the doors as the body is tilted and returning the doors to a closed position as the body is righted, such a mechanism has been shown in the drawings, but it is to be understood that this door controlling mechanism forms no part of my invention and that any other suitable door controlling mechanism may be used.

Referring now to the drawings where like reference characters refer to like parts, reference character 1 indicates a dump car having a dump body 2 tiltably mounted on an underframe 3 and tilting to either side thereof in dumping. At each side of the body and hinged adjacent the floor thereof are doors 4 forming the side walls of the body and having downward depending portions 6 spaced longitudinally of the doors to which the door locking mechanism is attached. The essential elements of the door locking mechanism comprise transverse arms 7 attached at one end to the downward depending door portions 6 and extending across the car body to an engagement with a member 8 pivotally mounted on the underframe at the side opposite said door and having one end in engagement with the body to control the movements of its respective arm 7 and door 4. These members 8 mounted on each side of the underframe have a link member 9 connecting the ends of the members opposite to the ends in engagement with the body to cause both members to be moved simultaneously when the one is moved through its engagement with the tilting body. These

transverse arms 7 are supported by the members 10 and 11 at each side of the body and the arms 7 move within these members as the side door to which they are attached is opened 5 and closed in discharging the lading carried by the body. The members 10 and 11 perform the additional function of holding the locking members 7 in position to maintain the inactive door closed while the body moves 10 in dumping.

With the body in horizontal position as shown in Fig. 1 and it is desired to tilt the body towards the right side of the underframe, the following operations take place:—

- 15 The body tilting mechanism (not shown in the drawings), of whatever type used, tilts the body towards the right side of the underframe and the member 8 on that side of the underframe remains in contact with the body 20 and moves towards the right side of the underframe simultaneously with the body. The member 8 on the left side of the underframe moves out of engagement with the left side of the body as the body rises and permits the 25 arm 7 in engagement with it to move transversely of the underframe from right to left and permits the door on the right side of the body to open by gravity and the weight of the lading being discharged. After the door 30 is released and begins to open the door operating mechanism mounted on the underframe engages with the door and controls the door throughout the remainder of its opening movements.
- 35 The member 8 on the right side of the underframe and in engagement with the right side of the body acts as a stop for the member 7 attached to the door on the left side of the body and prevents that member from moving 40 inwardly across the body to permit the door on the left side of the body to open. The members 10 and 11 mounted on the left side of the body hold the member 7, secured to the door on that side of the body, in contact with 45 its respective member 8 and at the same time support the free end of the member 7 secured to the opened door and hold it in operative position to engage with its respective member 8 when the body again resumes a position 50 horizontal with the underframe.

When the body tilting mechanism returns the body to a horizontal position, the return movement of the body moves the member 8 in engagement with the body inwardly and 55 through its attachment to the member 8 on the opposite side of the underframe, by means of the link member 9, that member on the opposite side of the underframe is moved into position to engage with the body. Si- 60 multaneously with the return of the body to a horizontal position, the door operating mechanism returns the door to a closed position so that both the doors are fully closed before the body has completed its return to 65 a horizontal position and the member 7 at-

tached to the closing door is moved inwardly across the car in its supporting members 10 and 11 a sufficient distance to permit the member 8 on the left side of the body to move into position between the members 10 and 11 and engage with the member 7 secured to the door on the right side of the body, locking it in closed position as the body comes to rest on the underframe. Simultaneously with the return of the body to an upright position, the door operating mechanism passes out of engagement with its respective door and the doors on each side of the body are again held in closed position only by the door locking members 7 in engagement with the members 8 mounted on the underframe.

When the body is tilted towards the left side of the underframe, the same movements of the respective members, as described above takes place excepting that the member 8 mounted on the right side of the underframe passes out of engagement with the body and the door on the left side of the underframe is permitted to open to discharge the lading and the discharging door is again locked in position as the body returns to horizontal position as previously described.

Having thus described the invention what I claim as new and desire to secure by Letters Patent is:

1. In a dump car, an underframe, a dump body mounted on said underframe in stable equilibrium, doors for said body hinged adjacent the floor thereof, downward depending members on said doors and a door locking mechanism for automatically and selectively releasing the descending door for opening as the car body is tilted in dumping, said mechanism comprising a stop member mounted on each side of the underframe and in engagement with the car body, a member mounted on the body having one end secured to a depending door member and the other end portion extending transversely of the car to a selective engagement with said stop member mounted on the opposite side of the underframe.

2. In a dump car, an underframe, a dump body supported directly on said underframe in stable equilibrium, means mounted at each side of the body and normally free of the underframe which engage with the underframe as the body is tilted and about which the body turns in dumping, doors for said body hinged adjacent the floor thereof, downward depending members on said doors, a door locking mechanism mounted on the body for automatically and selectively releasing the descending door for opening as the body is tilted and automatically locking the door when the door is closed upon the return of the body to a horizontal position, said mechanism comprising a member attached at one end to a depending door member and extending transversely of the car to a selective en-

gagement with a member pivotally mounted on the underframe, said underframe member having a selective engagement with the body and a suitable mechanism mounted on the 5 underframe for limiting the opening and effecting the closing of said doors.

3. In a dump car, an underframe, a dump body mounted on said underframe in stable equilibrium and tilting to either side in 10 dumping, side doors for said body hinged adjacent the floor thereof, downward depending members on said doors, a door locking mechanism for automatically and selectively locking and unlocking said doors as the body 15 is moved in dumping, said mechanism comprising a member mounted on the body and movable transversely thereof, a member pivotally mounted on each side of the underframe adjacent the depending door members, 20 said member mounted on the body having a connection at one end to a depending door member and at the other end having a selective engagement with the pivotally mounted underframe member at the opposite side of 25 the car.

4. In a dump car, an underframe, a dump body tiltably mounted on said underframe, side doors for said body hinged adjacent the floor thereof, downward depending members 30 on said doors, a member pivotally mounted at each side of the underframe and having a selective engagement with the body, a member mounted on the body having one end secured to a depending door member and extending 35 across the car body to a selective engagement with the opposite pivotally mounted underframe member and means mounted on the underframe for holding said pivotally mounted members in operative position.

40 5. In a dump car, an underframe, a dump body mounted on said underframe in stable equilibrium and tilting to either side in dumping, side doors for said body hinged adjacent the floor thereof, downward depending members 45 on said doors and a door locking mechanism for automatically and selectively controlling the locking and unlocking of the discharging door as the body moves in dumping, said mechanism comprising a member pivotally mounted on the opposite side of the underframe from its respective door, a member mounted on the body having one end in engagement with its respective door and the other end extending transverse- 55 ly of the body to a selective engagement with the opposite pivotally mounted underframe member, said members being out of engagement with each other during the time the door is open.

60 6. In a dump car, an underframe, a dump body mounted on said underframe in stable equilibrium and tilttable to either side in dumping, side doors for said body hinged adjacent the floor thereof, downward depending members 65 on said doors and a member

mounted on the body adjacent each side door, said member being connected at one end to said downward depending member and at the other end having a selective abutting engagement with a pivotally mounted portion of the opposite side of the underframe for automatically controlling the locking and unlocking of the discharging door as the body moves in dumping. 70

7. In a dump car, an underframe, a dump body mounted on said underframe and tilting to either side in dumping, side doors for said body hinged adjacent the floor thereof, downward depending members on said doors, a member mounted on said underframe at each side thereof and having a selective engagement with the body, a member mounted on said depending door members and extending transversely of the body, said body mounted member engaging with the member mounted on the opposite side of the underframe when said member is in engagement with the car body. 75

8. The combination in a dump car of an underframe, a body tiltably mounted on said underframe, side doors for said body hinged adjacent the floor thereof, a door locking mechanism attached to each side door and extending transversely of the body free of the underframe, a pivotally mounted stop member on the underframe at each side thereof, said door locking member engaging with the stop member on the opposite side of the underframe to hold its respective door in closed position. 80

9. The combination in a dump car of an underframe, a body tiltably mounted on said underframe, side doors for said body hinged adjacent the floor thereof and opening downwardly as the body is tilted, a door locking mechanism mounted on the body and having a selective engagement with the underframe for releasing the discharging door for opening as the body is tilted, said mechanism comprising a member pivotally mounted adjacent each side of the underframe and rotating in the direction of the tilting body, a member mounted on the body and extending transversely thereof, one end of said member being attached to a side door and the other end engaging with the member mounted on the underframe when the door is in closed position. 95

10. The combination in a dump car of an underframe, a body tiltably mounted on said underframe, side doors for said body hinged adjacent the floor thereof, and a door locking mechanism mounted on the body and having a selective engagement with the underframe for holding the door in closed position with the body horizontal and releasing the discharging door for opening as the body is tilted, said mechanism comprising a member secured to each side door and extending transversely of the body, and a stop member 110 115 120 125 130

mounted on each side of the underframe and engaging with the body when the body is horizontal, said member secured to each side door moving transversely of the underframe to permit its respective door to open as the body moves out of contact with its respective stop member.

11. In a dump car, an underframe, a body tiltably mounted on said underframe, side doors for said body hinged adjacent the floor thereof, a door locking mechanism mounted on said body for holding said doors in closed position, said mechanism comprising a compression member attached to each side door and extending transversely of the underframe, and a stop member mounted on the underframe at each side thereof, said transversely extending member moving out of engagement with the stop member at the side opposite the discharging door as the body moves in dumping.
